UNITED STATES PATENT OFFICE

156,657

FABRIC OR SIMILAR ARTICLE

Ferdinand N. Phillips, Jr., Brookline, Mass.

Application March 26, 1949, Serial No. 1,633

Term of patent 14 years

(Cl. D92—1)

To all whom it may concern:

Be it known that I, Ferdinand N. Phillips, Jr., a citizen of the United States of America, resident of Brookline, county of Norfolk, and Commonwealth of Massachusetts, have invented a new, original, and ornamental Design for Fabric or Similar Article, of which the following is a specification, reference being had to the accompanying drawing, forming a part thereof.

The figure is a plan view of a piece of the fabric, showing my new design.

The design unit is outlined by broken lines. Said design is repeated as indicated.

I claim:

The ornamental design for a fabric or similar article, substantially as shown and described.

FERDINAND N. PHILLIPS, JR.
